UNITED STATES PATENT OFFICE.

PAUL C. DELAIZE, OF NEW YORK, N. Y., ASSIGNOR TO D'ORSAY PERFUMERIES CORPORATION, OF NEW YORK, N. Y., A CORPORATION OF NEW YORK.

DESIGN FOR A BOTTLE.

Application filed April 1, 1926. Serial No. 17,148. Term of patent 3½ years.

To all whom it may concern:

Be it known that I, PAUL C. DELAIZE, a citizen of the United States, a resident of New York city, in the county of New York and State of New York, have invented a certain new, original, and ornamental Design for Bottles, of which the following is a specification, reference being had to the accompanying drawing, forming part thereof.

view; Figure 3 is a side elevation showing the places for the labels; Figure 4 is a side elevation of Figure 3 and Figure 5 is a rear elevation.

I claim:

The ornamental design for a bottle as shown.

In testimony that I claim the foregoing, I have hereunto set my hand this 27th day of March, 1926.

PAUL C. DELAIZE.
